UNITED STATES PATENT OFFICE.

BENJAMIN F. CRISENBERRY, OF ELWOOD, INDIANA.

SYRINGE.

No. 873,728.

Specification of Letters Patent.

Patented Dec. 17, 1907.

Application filed February 27, 1907. Serial No. 359,577.

To all whom it may concern:

Be it known that I, BENJAMIN F. CRISEN-BERRY, a citizen of the United States, residing at Elwood, in the county of Madison and 5 State of Indiana, have invented a new and useful Syringe, of which the following is a specification.

This invention relates to syringes of that type which have a receptacle for holding the 10 solution to be injected, detachably connected to certain devices partially operated by the movement of the injected solution to cause said solution to be discharged from the delivery end of said syringe into the farthest 15 end of the opening, canal, or duct under treatment; to then flow backward between the syringe nozzle and the wall of the affected opening, canal or duct toward the outlet thereof, and to finally return or be drawn into 20 the receptacle before any of said solution can escape from the cavity under treatment.

To this end the invention consists of a hollow resilient receptacle from which a tube leads provided with valves which open and 25 close certain outlets and ports under the movement of a solution forced through the tube when the receptacle is squeezed and then permitted to resume its normal shape.

In order that the construction and opera- 30 tion of the invention may be made clear a detailed description is herewith presented followed by definite claims and accompanied by a drawing in which,

Figure 1 is a view of the syringe partly in 35 elevation and partly in section. Fig. 2 is a cross section on the line 2—2 Fig. 1. Fig. 3 is a view in elevation of the nozzle or delivery tube detached. Fig. 4 is a perspective view of the valves and their connecting 40 stem.

Similar numerals of reference indicate corresponding parts in all the figures of the drawings.

The numeral 1 indicates a hollow resilient 45 approximately spherical receptacle, preferably made of rubber, with a flattened base 2 to hold the receptacle in upright position, and a tubular projecting neck 3 on the side opposite the base to neatly close the canal 50 opening and to receive one end of a nozzle 4 connected to said neck by a slip joint in order that the nozzle may be removed when a medicated solution or other liquid is to be placed in the receptacle. To strengthen the re- 55 ceptacle 1 and increase its elasticity, a plu-

rality of circumferential ribs 5 are formed integral therewith, as shown.

The nozzle 4 is tubular and comprises an outer cylindrical end 6, an inner cylindrical end 7 of greater diameter than the outer end 60 and a frusto-conical connection 8 with a number of spaced perforations 9 formed circumferentially through its wall, and in a plane perpendicular to the axis of the nozzle. Integral with or attached to the outside of the 65 outer end 6 and the frusto-conical connection 8 of the nozzle 4 are a series of tapering ribs 10, interspaced between the perforations 9 as clearly represented in Fig. 2. The ribs 10 begin a short distance back from the outlet 70 11 of the nozzle and extend downwardly in a divergent direction, to the base of the frusto-conical connection 8, extending outwardly at their lower ends a slight way beyond the inner nozzle end 7. These ribs are 75 to press against the soft parts of the wall of the opening into which the nozzle is introduced and hold back from the openings 9 any loose membranes or tissues which would tend to close said openings. Between the ribs are 80 ducts or chambers 12 along which the solution runs to the openings 9 into which the solution enters or is drawn by suction.

Axially disposed within the outer end 6 of the nozzle 4 is a valve stem 13, on the extreme end of which is secured a valve 14 adapted, when seated, to close the mouth 11 of the nozzle. The valve 14 is dome shaped on its outer or exposed side and cone shaped on its inner or under side, to seat firmly and 90 tightly against the inwardly beveled mouth 11 of the nozzle. The diameter of the valve 14 is that of the outer end 6 of the nozzle and is dome shaped on its exposed face to make easier the introduction of the instrument 95 into a part to be treated.

A valve 15, loosely supported on the lower end of the valve stem 13 by a screw 16 threaded into the end of said stem, has its periphery inclined at the same angle as the 100 frusto-conical section, against which it seats at certain times to close the openings 9. Passages 17 are formed through the valve 15 to permit the solution in the receptacle to pass said valve freely when the latter is seated. 105 The loose connection between the valve stem and the valve 15 allows the valve under all circumstances to close the openings 9 as soon as the receptacle is compressed, and thereby prevent the escape of the solution through 110

said openings. The distance between the valves 14 and 15 is regulated by turning the valve 14 on the threaded end of the valve stem 13.

- 5 To use the invention, the proper amount of liquid is placed in the receptacle 1 through the neck 3, after which the latter is slipped over the larger end 7 of the nozzle. The end 6 of the nozzle is then introduced a suitable distance into the cavity to be treated and the receptacle compressed. The valve 15 immediately seats itself, closing the openings 9 to prevent the escape of any of the liquid therethrough, and the valve 14 opens so that the 10 solution which has passed freely through the passages 17 may come in contact with the most distant parts of the affected part. After ejecting the solution, the receptacle is allowed to resume its normal form which produces a suction in the nozzle 4, closing the 15 nozzle 14 and retracting the valve 15. The openings 9 are thereby uncovered and the suction draws the liquid, running down the channels 12 and in contact with the walls of 20 the diseased cavity, through said openings into the receptacle again, thereby preventing the escape of any of the liquid, more or less impregnated with disease germs, from 25 escaping outside the affected part.
- 30 Having thus described the invention what is claimed is:—
1. The combination in a syringe, of a compressible bulb, a nozzle leading therefrom and provided near its extreme end with a discharge opening for fluid from the bulb and near its inner end with an inlet opening for fluid to pass to the bulb, both openings communicating with the single passage of the nozzle, valve seats at said openings, and a pair of 35 connected valves arranged to close in alternation on compression and release of said bulb.

2. A syringe comprising a resilient compressible receptacle, a nozzle having at each end a bore of different diameter connected by a tapering valve seat the latter being 45 perforated, an external and an internal valve loosely connected by a stem and adapted to operate alternatively to seat themselves, and external ribs on said nozzle.

3. A syringe comprising a resilient, compressible receptacle, a nozzle having a bore at one end larger than that at the other, said bores being connected by a tapering valve seat having circumferential openings through the wall of said seat, a valve for closing the 55 smaller bore of said nozzle having a valve stem, and a valve having passages therethrough loosely mounted on the inner end of said stem and adapted to close said circumferential openings.

4. A syringe comprising a resilient, compressible receptacle, a nozzle having a bore at one end larger than that at the other, said bores being connected by a tapering valve seat having circumferential openings through 65 the wall of said seat, a valve for closing the smaller bore of said nozzle having a valve stem, a valve having passages therethrough loosely mounted on the inner end of said stem and adapted to close said circumferential openings, and a series of longitudinally disposed tapering ribs on the outside of said nozzle arranged to form channels leading to 70 said circumferential openings.

In testimony that I claim the foregoing as 75 my own, I have hereto affixed my signature in the presence of two witnesses.

BENJAMIN F. CRISENBERRY.
